VENDING MACHINE

Marcus L. Holt, Lookout Mountain, Ga., assignor
of one-half to John B. Brock, Adairsville, Ga.

Application May 8, 1946, Serial No. 668,188

14 Claims. (Cl. 312—88)

1

This invention relates to vending machines and more particularly to such machines of the coin-controlled type adapted to dispensing of packaged goods, such as bottled beverages, canned goods and the like.

One of the objects of my present invention is to provide a coin-controlled vending machine wherein a quantity of articles to be dispensed is compactly carried in a plurality of adjacent columns within an enclosure for sequential and automatic vending therefrom, one at a time, under the control of a mechanism having provisions for insuring the delivery of an article or the return of the coin.

Another object of the invention is to provide a coin-controlled vending machine having adjacent sections within an enclosure for supporting columns of articles to be dispensed, each of which sections and its accompanying vending mechanism is adapted to handle articles of various sizes and shapes, within reasonable limits of variation.

For a further object, my invention comprehends the provision of a vending machine wherein the articles to be dispensed are disposed in columns and each column comprises a plurality of adjacent rows, from which rows the articles are fed to delivery positions by gravity and sequentially delivered under the control of a positively actuated delivery control mechanism.

It is another object of this invention to provide a vending machine including a control element adapted to actuation directly by the articles contained in and dispensed by the machine for effecting an indication when the machine is empty and normally for insuring the delivery of an article each time the machine is operated.

My invention also has for an object the provision of a vending machine having one or more of the features referred to and incorporating parts constructed and arranged to prevent pilfering of the articles therefrom.

Other objects and advantages of the invention will be apparent from the following description and the accompanying drawings in which similar characters of reference indicate similar parts throughout the several views.

In the five sheets of drawings:

Fig. 1 is a fragmentary front elevational view of a vending machine embodying a preferred form of my invention and having a front portion of the enclosure removed so as to show the interior working parts;

Fig. 2 is a fragmentary side view with a portion cut away substantially as indicated by an

2

irregular section line 2—2 in Fig. 1 and the accompanying arrows;

Fig. 3 is a top sectional view with the section taken substantially on a line 3—3 of Fig. 1;

Figs. 4 and 5 are fragmentary detail views drawn to an enlarged scale to depict the structure of parts of the mechanism illustrated in Figs. 1, 2 and 3;

Fig. 6 is a fragmentary front sectional view drawn to an enlarged scale of a portion of the mechanism shown in Fig. 1; and

Fig. 7 is a schematic circuit diagram illustrating the electrical connections between the parts of the illustrated vending machine.

15 In the exemplary embodiment of my invention which is shown in the accompanying drawings, I have illustrated its adaptation to the vending of bottled beverages. For the vending of any particular kind or size of article which is suited to 20 the use of the mechanism, the sizes of the parts and the type of enclosure are suited to the article. In the present instance, the bottled beverages are to be cooled before being dispensed. Hence, an outer enclosure 10, as indicated in Figs. 1, 2 and 3, comprises a cabinet having a front wall 12, side walls 13, back wall 14, and a top wall 15, all of which walls are made up of an outer covering of sheet metal 16 filled with heat insulating material 17. In the present adaptation a relatively 30 small opening 18 is provided at the front of the outer enclosure through which articles are dispensed. Above the opening 18 the front wall 12 of the outer enclosure desirably includes a panel 19 which is removable to provide access to the interior of the enclosure and which may be locked in position relative to the enclosure so as to be removable only by an authorized person.

Within the upper portion of the outer enclosure a rack, which is indicated generally by the reference numeral 20, carries the articles which are to be dispensed and supports the major portion of the vending mechanism. A chute 22 has a rear portion which underlies the rack 20 and slopes downwardly toward the inner end of the opening 18 to guide articles dispensed from the rack to an adjoining chute extension 23 which extends through the opening 18 and has an end flange 24 thereon which is desirably lined with resilient material, such as a strip of rubber 25, for stopping the articles as they are dispensed. This general arrangement of the parts leaves the lower portion of the outer enclosure for housing a suitable refrigerating mechanism (not shown).

In order to increase the rate of cooling of articles carried by the rack 20, an electric fan 26

is mounted within the upper rear portion of the outer enclosure for circulating the cooled air from the refrigerator unit across the retained articles. By preference, a baffle plate 27 (Fig. 2) extends over the fan in the upper rear corner of the enclosure to improve the circulation of the chilled air. In order to prevent undue heat loss through the opening 18, a door 28 of heat insulating material is supported for swinging movement by a hinge 29 at the top thereof so that it is swung outwardly by the movement of a dispensed article along the chute 22 and chute extension 23, and normally gravitates to its closed position when there is no obstruction, such as a dispensed article, to prevent its closing movement.

The rack 20 includes a substantially U-shaped base frame 30 having a relatively straight and rigid front portion 32 and relatively straight and opposed side portions 33 which are desirably formed integrally with the front portion and extend rearwardly in substantially parallel relationship. Angle strips 34 are secured to opposite outer surfaces of the base frame side portions 33 and are carried by angle strips 35 which are secured to opposite interior surfaces of the side walls 13 of the outer enclosure to support the rack. The rear ends of the base frame side portions 33 are secured to and connected by a sheet metal back plate 36 which provides a rear wall for the rack and has an opening 37 therein adjacent the fan 26 for the circulation of cooling air to the articles carried by the rack.

A plurality of substantially U-shaped bars 38 have straight intermediate portions 39 extending vertically along the inner surface of the back plate 36 and substantially parallel end portions 40 extending forwardly therefrom; the forward ends of the lower end portions being secured to the inner surface of the base frame front portion 32 and the forward ends of the upper end portions being secured to an upper cross bar 42. Bars 41 have their opposite ends secured to and extend upwardly between the front base frame portion 32 and the upper cross bar 42 in positions opposite the straight intermediate portions of the U-shaped bars 38. Laterally the U-shaped bars 38 are disposed in equally spaced relationship relative to one another and the outer ones of the bars are displaced from the base frame side portions by a distance substantially equal to half of the spacing between adjacent bars. Additional support bars 43 have their ends secured respectively to the base frame front portion 32 and the back plate 36 and extend from front to rear between the base frame side portions 33 in substantially parallel and equally spaced relationship so that they are midway between the U-shaped bars 38. A plurality of vertically disposed guide tubes 44, which are preferably rectangular in section, are disposed in spaced rows with their lower ends secured to the base frame side portions 33 and the support bars 43, and their upper ends secured to similar suitable frame members. The guide tubes 44 laterally define a plurality of similar article-carrying sections 45 adjacent one another within the rack. The lateral spacing of the guide tubes 44 is such that a plurality of articles 46 which are to be dispensed are carried therebetween in laterally spaced vertical rows, as shown in Figs. 3 and 6. As shown in Fig. 5, filler pieces 47 may be interchangeably connected to the surfaces of the guide tubes 44 to provide variations in the section widths to accommodate different sizes of articles in a single machine.

As shown in Figs. 1 and 3, the complete vend-

ing machine, in the present instance, includes four sections in side-by-side relationship, each of which sections holds two laterally displaced and vertically disposed rows of articles to be vended.

5 It may be readily appreciated that the number of sections may be varied and, as will be more fully set forth, the sections may be either individually controlled or operated in multiple so as to dispense articles sequentially.

10 In order to provide separation between the articles in each row in each of the sections and so as to separate the articles of adjacent rows from one another, I have provided each section with a series of vertically separated spacer bails

15 48 and a retaining bail 49, each of which bails has aligned end portions 50 and 52 (Fig. 2) and a substantially straight mid-portion 53 which is offset from the aligned end portion. The spacer bails 48 and the retaining bail 49 have their

20 aligned end portions 50 rotatably supported in aligned openings 54 in the bars 41 and the straight intermediate portions 39 of the U-shaped bars 38 so that the bails extend longitudinally of the sections from end to end and are normally

25 midway between the guide tubes 44. Thus the bails are supported for swinging movement laterally of the sections.

By preference, each of the bails, except the lowermost two, has a roller 55 of resilient mate-

30 rial, such as rubber, rotatably mounted on the straight mid-portion thereof, each of which rollers serves the dual purpose of providing a cushioning surface for engagement with the articles and a rolling surface to facilitate the passage of articles downwardly through each section. Al-

35 though such rollers of resilient material would normally be quite desirable and effective on the lowermost two of the bails, those two have been excepted in the present instance in order to pro-

40 vide insurance against pilfering of the machine by gaining access through the dispensing opening 18 and removing the rollers by cutting. To prevent such unwarranted release of articles and be-

45 cause the lowermost two of the bails are exposed below the rows of articles, I have provided metallic rollers 56 on those lowermost two of the bails, which metallic rollers are preferably made of spir-

46 ally wound wire or the like. It may be under-

50 stood that the cutting away or removal of one of the exposed rollers might well provide sufficient space for articles to pass from the sections at one or both sides of the bails.

55 In the normal operation of my vending ma-

chine, the articles to be dispensed are put into the sections from the top and placed alternately on opposite sides of the bails in each section. The retaining bail at the lower end of each section controls the release of the articles from that section and has its position determined so that

60 it is angularly disposed to one side or the other of the bar 41 to retain the lowermost article in the section on the side thereof toward which its mid-portion extends. As depicted in Fig. 6, the determination by the retaining bail of the

65 row in which the lowermost article of each section is retained also determines the positions of the remaining articles in that section and the bails carrying rollers which intervene between the remaining articles. The rollers above that

70 on the retaining bail are each interposed be-

75 tween adjacent articles of the two rows; those

rollers and the accompanying bails being biased to that position by the weight of the supported articles. Each time the retaining bail is shifted

75 from a position supporting the lowermost article

in one row to a position of support for the lowermost article in the adjacent row, the lowermost article in the section is released and the remaining articles gravitate downwardly and shift the angular positions of the upper-bails to their succeeding positions of support during the movement of the articles.

In order to provide definite control and positive actuation for determining the positions of the retaining-bails 49 for each of the sections, I have provided each of those retaining-bails with a crank-like end portion 57 which engages and coacts with one of a series of driven cams 58, 59, 60 and 62. In the disclosed embodiment of my invention, the dispensing of articles from two sections on one side of the machine is controlled by one operating mechanism while the dispensing of articles from the two sections on the other side of the machine is controlled by another operating mechanism. Hence the cams 58 and 59 are secured to a shaft 63 which is rotatably supported by bearings 64 and 65 and drivingly connected at one end to a motor 66. The cams 60 and 62 are secured to a shaft 67 which is rotatably supported by the bearing 65 and a bearing 68 and drivingly connected at one end to a motor 69. The bearings 64, 65 and 68 have integral flanges 70, 72 and 73, respectively, which are integrally formed thereon and secured to the front surface of the base frame 39 so that the shafts 63 and 67 extend laterally across the lower front portion of the rack in end-to-end relationship, the bearing 65 providing a common support for the ends of the two shafts. Brackets 74 and 75 on the housings of the motors 66 and 69, respectively, are also secured to the base frame 39 to support those motors in positions for driving connections with outer opposite ends of the two shafts.

As depicted in Figs. 1, 3 and 6, the cams 60 and 62 have cam tracks in the form of channels 76 and 77, respectively, defined by separated and opposed flanges 73 on the cam 60 and similar spaced and opposed flanges 79 on the cam 62. The channel 76 of the cam 60 has actuating portions 80 in diametrically opposed positions and dwell portions 82 in diametrically opposed positions. Likewise, the channel 77 of the cam 62 has actuating portions 83 in diametrically opposed positions and dwell portions 84 in diametrically opposed positions. The projecting tips of the crank-like end portions 57 on the retaining-bails 49 ride in the channels 76 and 77 of the cams 60 and 62, respectively, and have their positions determined thereby.

In order to provide relatively quick actuation of the retaining-bails from one article-retaining position to the other and so as to provide longer periods during which the retaining-bails are held in one or the other of their retaining positions, the dwell portions of the channels are relatively long and cover a substantial portion of each half of a cam revolution, while the actuating portions of the channels are relatively short circumferentially of the cam and are disposed in relatively sharp angular relationship to the dwell portions. The axial length of the actuating portions of the channels is sufficient to effect the movement of each of the retaining-bails from a position underlying one row of articles to a position underlying the adjacent row of articles in that section. The cams 58 and 59 are respectively similar in construction and operation to the cams 62 and 60, respectively,

and similar portions are referred to by like reference numerals.

In order to provide a larger quantity of one type of article to be dispensed by a single mechanism and for the purpose of providing greater assurance of the delivery of an article at each operation of the machine, I prefer to have the two cams on each shaft, such as the cams 60 and 62 on the shaft 67, displaced with respect to one another by 90 degrees so that the articles will be dispensed sequentially from the two sections controlled by those cams. In a similar manner the cams 58 and 59 on the shaft 63 are also desirably displaced 90 degrees relative to one another so that one of the cams actuates its coacting retaining-bail while the other retaining-bail is held in one of its article-retaining positions. By making the dwell portions of the cams considerably longer than the actuating portions in a direction circumferential of the cams, the possibility of double or overlapping operation is avoided and a safety factor is provided to allow for overrunning of the motor after it has been deenergized.

Since the machine disclosed herein embodies separately driven and operable vending mechanisms for dispensing articles through a single outlet chute, I have provided a partition 85 which is supported by the rack and extends downwardly toward the chute 22 to prevent the collision or jamming of articles in the chute 22 and within the opening 18.

My preferred system of control for each driven unit of the disclosed vending machine may be readily understood by reference to the schematic circuit diagram shown in Fig. 7, wherein I have illustrated the electrical connections between parts when the mechanism is adapted to coin-controlled operation. A conventional coin slide is depicted schematically at 86. This coin slide desirably embodies an electromagnetic coin rejector 87 having a winding 88, as well as a coin operated switch 89. The deposit of a coin in the slide 86 momentarily closes the switch 89 to close a circuit from power supply line leads 90 and 92 to an actuating winding 93 of an electromagnetically operated relay 94 through that switch and the normally closed contacts of a switch 95.

The electromagnetically operated relay 94 operates quickly in response to energization through the switch 89 to open the circuit to the coin rejector winding 88 through contacts 96 and to close a holding circuit to the actuating winding 93 through contacts 97. The closing of the holding circuit to the actuating winding 93 maintains the energization of that actuating winding after the coin has passed the switch 89 and allowed the contacts of that switch to return to their normally open position. The energization of the actuating winding 93 of the relay 94 also closes a circuit from the power supply line lead 90 to one terminal of the motor 69 through the contacts 97 and closes a circuit from the power supply line lead 92 to the other terminal of the motor 69 through contacts 98. The motor 69 then remains in operation until the switch 95 is opened to effect deenergization of the actuating winding of the relay 94. As will be more fully explained, the switch 95 is controlled by the release of an article from one of the sections from which the motor 69 controls such release. The release of an article thus effects the return of the circuit to its normal starting condition for operation 75 upon the deposit of a succeeding coin.

A switch 99 having contacts 100 and 102 normally closes a circuit through the contact 100 from the power supply line lead 90 to the coin rejector winding 88. When the coin rejector winding is thus energized, normal operation of the coin slide occurs upon the deposit of a coin. However, when the coin rejector winding 88 is deenergized, as it is during the operation of the motor 69, or when the circuit thereto through the switch 99 is broken, or even in the instance of a power failure, the coin is returned to the depositor through a suitable coin return chute.

When both of the sections controlled by the motor 69 are empty, the switch 99 not only breaks the circuit to the coin rejector winding so that the coin will be returned, but it also closes a circuit through contact 102 to a signal light 103. The signal light provides an indication that the portion of the machine which is controlled through the coin slide 86 is empty.

By reference to Fig. 2 it may be observed that the switches 95 and 99, which have been referred to in connection with the circuit diagram disclosed in Fig. 7, are mounted in spaced relationship on brackets 104 and 105, respectively, and in spaced relationship at the rear of the rack. A vane 106 is supported for rotary movement on a shaft 107 which extends laterally of the sections and is spaced somewhat below the lower ends of the sections. This vane has forwardly projecting arms 108 which underlie each of the sections controlled by one of the motors. On the opposite side of the shaft 107 from the arms 108 each vane has a rearwardly projecting portion 109 which carries a weight 110, which weight normally biases the arms 108 toward the sections which they underlie and is sufficiently heavy to effect operation of the switch 99 when the actuating element 112 of that switch is engaged by the lower surface of the rearwardly projecting portion 109 of the vane.

In the operation of the mechanism, each of the vanes 106 is biased by its weight 110 to a position, such as that indicated in solid lines in Fig. 2, in which position at least one of the arms 108 is in engagement with the lowermost article in one of the sections and both of the switches 95 and 99 are in their normal positions which are indicated in Fig. 7. If both sections which are controlled by the motor 69 are empty so that there is no bottle for any one of the arms 106 to engage, the arms move to an abnormal angular position, such as that indicated in dot and dash lines at 108a, and the rearwardly projecting portion moves downwardly to a position, such as that indicated by dot and dash lines at 109a, to effect operation of the switch 99, as described, to open the circuit to the coin rejector winding 88 and close the circuit to the signal light 103.

When there are articles in the section and one of them is released upon the deposit of a coin so that it drops through a position such as that indicated at 46a and then falls to the slide, the weight of that released article overcomes the biasing force of the weight 110 and moves the arm of the vane downwardly to a position such as that indicated at 108b, whereupon the rearwardly projecting portion of the vane moves upwardly, as indicated at 109b, to a position such that the weight 110 engages the switch 95 and thereby opens the circuit to the motor to stop the dispensing mechanism.

From the foregoing description it may be understood that through the sequential operation of a plurality of sections by a single prime mover

which is under the control of an element responsive to the release of an article from one of the sections for effecting stoppage of the prime mover, a factor of insurance is provided that an article will be delivered upon each deposit of a coin when the machine is not empty. That is, if one section is empty or if for some abnormal reason an article fails to be released upon the operation of one of the retaining bails, the prime mover will not be stopped until an article has been released from the other section. On the other hand, the release of one article upon the deposit of a coin definitely insures the stoppage of the machine so that only one article will be dispensed for each coin deposited.

16 While I have illustrated a preferred embodiment of my invention, many modifications may be made without departing from the spirit of the invention, and I do not wish to be limited to the 20 precise details of construction set forth, but desire to avail myself of all changes within the scope of the appended claims.

Having thus described my invention, what I claim as new and desire to secure by Letters Patent of the United States is:

1. In a coin-controlled vending machine for articles of generally circular cross section, the combination comprising vertically disposed guides defining sections in side-by-side relationship, vertical support strips at opposite ends of each of said sections and substantially midway between the guides for each section, series of spacing bails each having aligned end portions and mid-portions offset from said end portions, the end portions of said bails being supported for swinging movement and in equally spaced relationship by the strips at opposite ends of each of said sections so that said bails extend longitudinally of the sections with their mid-portions normally depending below their respective aligned end portions, the spacing of said bails being somewhat less than the cross-sectional dimension of one of said articles and the width of each section being so related to the cross-sectional dimension of said articles that the articles in each section are carried in displaced vertical rows with the mid-portions of said bails separating the adjacent articles of each row and of the adjacent rows from one another, the lowermost one of the bails in each section having a crank type end portion thereon extending outwardly from one of said strips, a shaft extending laterally of said sections near said crank type end portions, means for rotatably supporting the shaft, cams secured to said shaft and coacting with each of said crank portions to control the position of the lowermost bail in each section so that it normally supports the lowermost article in one or the other of the rows, and means for driving the shaft and cams to effect the shifting of the lowermost bails in each section from a position of support for the lowermost article in one of the rows to a position of support for the lowermost article in the other of the rows, whereby one article is released from each section upon each shift of the lowermost bail and the upper articles in the section gravitate downwardly, and said cams being so disposed relative to one another that said articles are released from the sections sequentially.

70 2. In a coin-controlled vending machine for
articles of generally circular cross section, the
combination comprising vertically disposed guides
defining an article-carrying section, vertical
support means at opposite ends of said section,
75 a series of spacing bails each having aligned end

portions and substantially straight mid-portions offset from said end portions, the end portions of said bails being rotatably supported by said support means in vertical alignment and equally spaced relationship substantially midway between said guides so that said bails extend longitudinally of the section with their mid-portions normally depending below their respective aligned end portions, the mid-portions of all but the lowermost two of said bails having non-metallic cushioning rollers rotatably carried thereon, said lowermost two of the bails having spirally wound metallic rollers rotatably carried thereon, said bails and guides being adapted to carry said articles in staggered relationship in the section providing displaced vertical rows of said articles with the mid-portions of said bails and said rollers separating the adjacent articles of each row and the articles of adjacent rows from one another, the lowermost one of the bails having control means drivingly connected thereto, and means for actuating said control means to shift the mid-portion of the lowermost bail from a position of support for the lowermost article in one row to a position of support for the lowermost article in the other row, whereby the lowermost article in the section is released upon each shift of the lowermost bail and the upper articles in the section gravitate downwardly and effect swinging movement of the upper bails.

3. In a vending machine for articles of generally circular cross section, the combination comprising guide means for laterally defining an article-carrying section, support means at opposite ends of said section, a series of spacing bails each having aligned end portions and substantially straight mid-portions offset from said end portions, the end portions of said bails being rotatably supported by said support means in aligned and equally spaced relationship substantially midway between said guide means so that said bails extend longitudinally of the section with their mid-portions normally depending below the respective aligned end portions thereof, the mid-portions of said bails having rollers rotatably carried thereon, said bails and said guide means being adapted to carry said articles in staggered relationship in the section so as to provide displaced rows of said articles on opposite sides of the bails with said rollers separating the adjacent articles of each row and the articles of adjacent rows from one another, the lowermost one of said bails having an end extension outside of said section and angularly disposed with respect to one of the aligned end portions thereof, cam means coacting with said end extension for actuating the lowermost bail between two article-supporting positions, one of said positions being such that the lowermost bail is inclined toward one of said rows of articles and the other position being such that the bail is inclined toward the other row of articles, said lowermost bail supporting the lowermost article in the section in each of said positions and releasing said lowermost article upon movement from one to the other of said positions, power driven means for actuating said cam means, means for effecting energization of said power driven means, and movable means normally biased toward the lowermost article and actuated by said lowermost article when it is released for effecting deenergization of said power driven means.

4. In a vending machine as characterized by claim 3, the combination including signal means, and means controlled by said movable means for

10
effecting operation of the signal means when said section is empty.

5. In a vending machine as set forth in claim 3, the combination wherein the rollers on the lowermost two of said bails comprise metallic means.

6. In a vending machine for vending articles of generally circular cross section, the combination comprising means for defining adjacent upright article-carrying sections open at the top and bottom, a series of vertically separated article-spacing elements disposed in a row dividing each of said sections into two columns related in width to the size of the articles to be dispensed, means for supporting each of said spacing elements for movement laterally of said sections, said spacing elements having their lateral positions determined by articles inserted alternately in said columns from the top, said spacing elements normally being laterally movable an amount sufficiently separately to pass an article in the column on either side thereof, said sections and said spacing elements being adapted to carry said articles in staggered relationship in said columns, article-retaining means at the lower end of each section, means for supporting the article-retaining means for each section for lateral movement between positions underlying one or the other of said columns of its respective section, power driven means, and cam means actuated by said power driven means for positively determining the position of each of said article-retaining means.

7. In a vending machine characterized by the combination defined in claim 6, said cams each having dwell and actuating portions and being so disposed and proportioned relative to one another that said article-retaining means of the sections are actuated sequentially.

8. In a vending machine for vending articles of generally circular cross section, the combination comprising means for defining adjacent upright article-carrying sections open at the top and bottom, a series of vertically separated article-spacing elements disposed in a row dividing each of said sections into two columns related in width to the size of the articles to be dispensed, means for supporting each of said spacing elements for movement laterally of said sections, said spacing elements having their lateral positions determined by articles inserted alternately in said columns from the top, said spacing elements normally being laterally movable an amount sufficient separately to pass an article in the column on either side thereof, said sections and said spacing elements being adapted to carry said articles in staggered relationship in said columns, article-retaining means at the lower end of each section, means for supporting the article-retaining means for each section for lateral movement between positions underlying one or the other of said columns of its respective section, each of said article-retaining means being adapted to support the lowermost article in its respective section when underlying the column in which the said lowermost article is disposed and effecting release of said lowermost article when moved to said position underlying the adjacent column, power driven means, means driven by said power driven means for positively actuating each of said article-retaining means separately and in sequence, means for effecting energization of the power driven means, and means actuated by the release of an article from one

of the sections for effecting deenergization of the power driven means.

9. In a vending machine having articles of generally circular cross section supported between guides in laterally displaced rows and in vertically staggered relationship, the combination comprising a bail type article-retaining element having an axis of swinging movement substantially midway between said guides and a mid-portion depending below said axis, means supporting said article-retaining element for swinging movement about said axis to positions such that said mid-portion thereof underlies one or the other of said rows of articles, in each of said positions said article-retaining element being adapted to engage and support the lowermost of said articles between the guides and thereby supporting the upper articles, said article-retaining element effecting release of said lowermost article upon movement to the other position, a cam having dwell and actuating portions, means for drivingly connecting said article-retaining element to said cam so that said actuating portions thereof effect movement of the article-retaining element between said positions, and power driven means for driving said cam.

10. In a vending machine having articles of generally circular cross section supported between guides in laterally displaced rows and in vertically staggered relationship, the combination comprising a bail type article-retaining element having an axis of swinging movement substantially midway between said guides and a mid-portion depending below said axis, means supporting said article-retaining element for swinging movement about said axis to positions such that said mid-portion thereof underlies one or the other of said rows of articles, in each of said positions said article-retaining element being adapted to engage and support the lowermost of said articles between the guides and thereby supporting the upper articles, said article-retaining element effecting release of said lowermost article upon movement to the other position, a cam having dwell and actuating portions, means for drivingly connecting said article-retaining element to said cam so that said actuating portions thereof effect movement of the article-retaining element between said positions, power driven means for driving said cam, means for effecting energization of said power driven means, an article-dispensing chute disposed below said guides, and means actuated by the passage of an article from between said guides to said chute for effecting deenergization of said power driven means.

11. In a vending machine having articles of generally circular cross section supported between guides in laterally displaced rows and in vertically staggered relationship, the combination comprising a bail type article-retaining element having an axis of swinging movement substantially midway between said guides and a mid-portion depending below said axis, means supporting said article-retaining element for swinging movement about said axis to positions such that said mid-portion thereof underlies one or the other of said rows of articles, in each of said positions said article-retaining element being adapted to engage and support the lowermost of said articles between the guides and thereby supporting the upper articles, said article-retaining element effecting release of said lowermost ar-

ticle upon movement to the other position, a cam having dwell and actuating portions, means for drivingly connecting said article-retaining element to said cam so that said actuating portions thereof effect movement of the article-retaining element between said positions, power driven means for driving said cam, electrically operated signal means, a switch for controlling the operation of the signal means, a movable switch-actuating element underlying both rows between said guides, and means for biasing said switch-actuating element toward the rows so that it normally engages said lowermost article, said switch-actuating element controlling said switch to effect operation of the signal means when the rows are empty.

12. In an article vending machine, the combination comprising guides defining adjacently disposed sections through which said articles normally gravitate from top to bottom, each of said sections being of a width to hold a plurality of laterally displaced rows of articles, a series of laterally movable elements in each section for retaining the articles of said rows in staggered relationship, laterally shiftable means for each of said sections for normally retaining said articles in the sections by engagement with the lowermost one of the articles in the section, power driven means for laterally shifting the laterally shiftable means in sequence to effect sequential release of said lowermost articles, means for energizing the power driven means, and control means dependent upon the release of one of said articles for deenergizing the power driven means.

13. In an article vending machine, the combination comprising guides defining adjacently disposed sections through which said articles normally gravitate from top to bottom, each of said sections being of a width to hold a plurality of laterally displaced rows of articles, a series of laterally movable elements in each section for retaining the articles of said rows in staggered relationship, laterally shiftable means for each of said sections for normally retaining said articles in the sections by engagement with the lowermost one of the articles in the section, power driven means for laterally shifting the laterally shiftable means in sequence to effect sequential release of said lowermost articles, means for energizing the power driven means, control means dependent upon the release of one of said articles for deenergizing the power driven means, signal means, and means for effecting control of said signal means by the control means to indicate when the sections are empty.

14. In an article vending machine, the combination comprising guides defining a section through which said articles normally gravitate from top to bottom, said section being of a width to hold a plurality of laterally displaced rows of articles, a series of laterally movable elements in said section for retaining the articles of said rows in staggered relationship, laterally shiftable means for normally retaining said articles in the section by engagement with the lowermost one of the articles in the section, the lowermost one of said laterally movable elements and said laterally shiftable means including metallic article-engaging rollers, and the other laterally shiftable elements having cushioning rollers thereon.
